Application May 28, 1936, Serial No. 82,230

9 Claims. (Cl. 257—178)

This invention relates to heat exchange apparatus, and particularly to cooling apparatus of the multiple tube type suitable for use in the manufacture of sulfuric acid.

5 The principal objects of the invention are to provide for improved operating efficiency of heat exchange apparatus of the kind described, to provide for construction facilitating manufacture of coolers of the tube type having improved rigidity, and to provide for simplified construction not only reducing operating but also manufacturing and installation costs.

10 The invention comprises the features of construction, combination of elements, and the arrangement of parts exemplified in the construction hereinafter set forth.

15 For a fuller understanding of the nature and objects of the invention, reference is made to the following description taken in connection with the accompanying drawings, in which

20 Fig. 1 is a perspective of the improved heat exchange apparatus;

25 Fig. 2 is a perspective of part of one tube unit showing the construction of individual tubes and the grouping of the tubes with respect to each other;

Fig. 3 is a horizontal cross-section taken on the line 3—3 of Fig. 2;

Fig. 4 is a horizontal cross-section taken on the line 4—4 of Fig. 2;

Fig. 5 is a front elevation of a tube unit; and

25 Figs. 6 and 7 are horizontal cross-sections, similar to Figs. 3 and 4, illustrating a modification.

30 Referring to Fig. 1, the heat exchange apparatus of the invention includes two tube units indicated generally by reference numerals 10 and 11. Unit 10 comprises a plurality of vertically disposed tubes 12, shown diagrammatically in

35 Fig. 1, opening into the under side of upper inlet header 13, having a closed rear end 14 and an open forward end 15 adapted to be connected to a fluid inlet pipe not shown. The bottoms of tubes 12 open into the top of an upwardly extending portion 18 of a continuous U-shaped bottom header 20 extending the length of the apparatus.

40 The upper ends of vertical tubes 21 of tube unit 11 communicate with an upper outlet header 23 closed at the forward end 25, and open at the rear end 26 for connection to a fluid outlet pipe not shown. The lower ends of tubes 21 of unit 11 open into the other upwardly extending portion 28 of the U-shaped bottom header 20. A supporting framework comprising cross-pieces 30, 31,

45 32 and 33 and longitudinal sills 34, 35, 36, and 37

5 rest on a framework not shown, for example transverse beams beneath the ends of sills 34, 35, 36, and 37. The vertical tubes and top headers of units 10 and 11 are supported in the relationship shown in Fig. 1 by posts 40 and the associated tie-rods 41.

10 Mounted on the top side of upper headers 13 and 23 are longitudinal overflow troughs 44 into which a cooling liquid such as water may be introduced from a pipe connection not shown. Reference numeral 45 represents a generally rectangular water sump positioned beneath the cooler in such a way as to collect all of the water flowed down over the outer surfaces of the tubes from troughs 44. Passing through the horizontal portion of the U-shaped bottom header 20 are several vertical pipes or passages 47 through which water collecting on the upper side of the bottom header 20 flows into sump 45. The apparatus is placed on the supporting framework in 15 such a way that the forward end is slightly lower than the rear so that condensate collecting in the continuous U-shaped bottom header 20 may be drawn off thru an outlet pipe 49.

20 Fig. 2 illustrates in perspective part of unit 11 25 (of Fig. 1) and shows upper header 23, four vertical tubes 50, 51, 52, and 53, and the upper part of the vertical portion 28 of the bottom header 20. For convenience in the present discussion, dot-dash line 55 of Fig. 2 may be considered as 30 the longitudinal axis of the bottom header of tubes 50, 51, 52, and 53.

25 Each individual tube, e. g. tube 50, is made by indenting or compressing an initially cylindrical tube at intervals to form a plurality of throats or 35 constrictions 58, 59, 60, 61, and 62 connecting a series of what may be considered enlarged chambers 63, 64, 65, and 66. Fig. 3 shows a horizontal cross-section through adjacent tubes 50 and 51 taken on the line 3—3 of Fig. 2, and Fig. 4 shows 40 a horizontal cross-section through tubes 50 and 51 on the line 4—4 of Fig. 2 through the next series of restrictions subjacent to the restrictions shown in Fig. 3. From Figs. 3 and 4 it will be seen that the tubes are indented so that restrictions form elongated throats having parallel 45 side walls. As shown in Fig. 3, the horizontal axis 70 of throat 59 of tube 50 lies in a horizontal plane disposed at a right angle to the vertical axis of tube 50. The axis 71 of the next lower 50 throat 60 of pipe 50 also lies in a horizontal plane perpendicular to the vertical axis of tube 50, but as shown in Fig. 4, axis 71 is disposed at a right angle to axis 70 of the next upper throat 59. Consequently all of the axes of throats of a 55

given tube are horizontal, and the axis of any one throat is disposed at a right angle with reference to the axis of an adjacent upper or lower throat.

In Figs. 3 and 4, the dot-dash lines 55 represent the longitudinal axis of the lower header portion 28, and dot-dash lines 75 and 76 represent the horizontal axes of throats 78 and 79 of tube 51. In accordance with the invention, the tubes comprising a given unit are grouped so that as to adjacent tubes of a unit, (e. g. tubes 50 and 51, Figs. 2, 3, and 4) adjacent tube throat axes lying in a common horizontal plane are disposed at an angle to each other and at an angle to the vertical plane of such adjacent tubes, or in other words, at an angle to the vertical plane of the unit proper. Thus, as shown in Fig. 3, throat axes 70 and 75 lie in a common horizontal plane, and are disposed at an angle to each other and at an angle to the vertical plane including the longitudinal axis 55 of lower header portion 28, the vertical axes of the tubes and the longitudinal axis 82 of upper header 23. Similarly, (Fig. 4) throat axes 71 and 76 lie in a common horizontal plane, and are disposed at an angle to each other and at an angle to the vertical plane including the vertical axis of the tubes and longitudinal header axes 55 and 82. In the embodiment of the invention illustrated in the drawings, throat axes 70 and 75 (Fig. 3) are disposed at an angle of 90° to each other and at an angle of 45° to the vertical plane of the tubes. The same relationship exists with respect to axes 71 and 76 of the adjacent lower throats 60 and 79.

By arranging the tubes as shown in Figs. 2, 3, and 4, it will be seen that throat axes 70 and 75 (Fig. 3) intersect, or in other words the ends of throats 59 and 78 contact at point 85. Likewise, throat axes 71 and 76 of Fig. 4 intersect, and the ends of throats 60 and 79 contact at point 86. In practice, the tubes may be initially of relatively large diameter, for example 4 to 12 inches. The tube walls are usually relatively thin, and in many instances may be made of some particular metal to withstand corrosive effects of materials being handled, as for example in the cooling of SO₂ burner gases in the manufacture of sulfuric acid, in which case the tubes may be made of lead. Thin walled lead tubes of such relatively large cross-section possess no material inherent rigidity and in a large unit would be likely to collapse in the absence of elaborate and expensive framework. The grouping of the tubes in accordance with the invention permits construction of the unit in such a way that tendency of the tubes to collapse is reduced to practically nothing and the amount of supporting framework may be minimized. By reason of the grouping of the tubes, all of the tubes of a unit may be connected together to form a rigid structure by spot welding or otherwise attaching adjacent tubes at each point of contact of the ends of the horizontal throat axes. In Fig. 3, the ends of throats 59 and 78 are spot welded at point 85, and in Fig. 4 the ends of throats 60 and 79 are spot welded at 86. Spot welds 85 and 86 and other spot welds, for example 87, 88, 89, 90 and 91 are indicated on Fig. 2.

From a consideration of Figs. 2, 3, and 4 it will be seen that in each unit, adjacent tubes are connected by spot welds lying in vertical planes the horizontal projections of which are represented by dot-dash lines 95 and 96 of Figs. 3 and 4. Thus, with respect to tubes 50 and 51,

spot welds 86 and 88 lie in a vertical plane represented by line 96, and spot welds 85 and 87 lie in a vertical plane represented by line 95. By this arrangement, adjacent tubes are attached in vertical planes spaced substantially to the front and rear of the vertical plane including the vertical axes of the tubes and the horizontal axes of the headers. The resulting structure has much more strength and rigidity than would be possible to obtain if the tubes were arranged in such fashion that the points of contact between adjacent tubes all were to lie in a single vertical plane, for example the vertical plane including the vertical axes of the tubes and the longitudinal axes of the upper and lower headers. Furthermore, all contacts of the tubes are point contacts as distinguished from line contacts. Additionally, the points of contact, by reason of their position at the ends of the throat axes do not split or divide into streams a thin film of liquid flowed down over the outer, warped surfaces of the tubes for cooling, for example, gas flowing thru the tubes.

While it is preferred to construct the heat exchange apparatus so that individual tubes are grouped with respect to each other as described in connection with Figs. 2, 3, and 4, other arrangements of adjacent tube grouping may be employed and at the same time secure the advantages of the invention. For example, in the horizontal cross-sections of Figs. 6 and 7, corresponding in a general way with the horizontal cross-sections of Figs. 3 and 4, the horizontal throat axes 101 and 102 of throats 103 and 104 of tubes 105 and 106 lie in the same horizontal plane and are disposed at an angle of 120° to each other and at an angle of 30° with respect to the dot-dash line 107 representing the horizontal projection of a vertical plane passing through the vertical longitudinal axes of the tubes. As shown in Fig. 7, the horizontal throat axes 110 and 111 of throats 112 and 113 are likewise disposed at an angle of 120° to each other and at an angle of 30° to dot-dash line 107. Whereas in tube 50, (Figs. 3 and 4) adjacent throats of a given tube are disposed at an angle of 90° to each other, in the modification throats 103 and 112 of tube 105 are disposed to each other in the 60° or 120° angular relation shown in Figs. 6 and 7. In the modified construction of Figs. 6 and 7, it will be seen that the horizontal throat axes lying in a given horizontal plane intersect and the ends of the throats approximately touch (as in Figs. 3 and 4) thus making possible spot welding as at points 115 and 116, or in other words, in vertical planes spaced substantially to the front and to the rear of the vertical plane passing through the vertical longitudinal axes of the tubes.

Individual tubes used to make up the cooler unit such as shown in Figs. 2, 3, and 4 may be made from cylindrical tubes of any suitable material and of any desired length and diameter. In the preferred embodiment of the invention of Figs. 2, 3, and 4, individual tubes may be made from cylindrical lead tubes, having an initial diameter of about 6 inches, by flattening the tubes at about 7½ inch intervals at an angle of about 90° between successive throats or crimps. The tubes may be crimped so as to provide about half inch clearance between the inner elongated parallel walls of the throats. Fluid flowing through the tubes has a high velocity while passing through the throats and then a much lower velocity while passing through the expanded

chambers intermediate the throats. Gaseous, vaporous, or liquid medium passing through the tubes is subjected to extremely vigorous turbulence and mixing, thus favoring efficient transfer of heat to or from the walls of the tubes depending upon whether the apparatus is used to cool or to heat the material flowing through the tubes. In the case of tubes of the type and size mentioned, the ratio of the cross-sectional area of the tubes to the cross-sectional area of the throats is about 6.25:1. By making the tubes so that the successive throats of a given tube are at an angle of about 90° as in the preferred construction, it is practically impossible for the fluid passing through the tubes to core, since the ratio of the cross-sectional area of the tube to the direct unobstructed passageway through the tubes is about 113:1. Accordingly, fluid flowing through the tubes is constantly subjected to changing forces, causing efficient mixing and substantial elimination of film formation on the inner walls of the tubes. While 6 inch tubes crimped at intervals of about 7½ inches have been mentioned, other ratios of tube diameter to distance between successive throats may be employed although the ratio of diameter to distance between successive throats should be about five to four or more.

The apparatus of the invention may be used for cooling or heating liquids and gases; for condensing of vapors from gases; for removal of finely divided liquids or solids from a gas stream; for mixing gases, mixing liquids, gases and liquids, and liquids and solids; and for absorption or stripping gases or vapors by liquids. The apparatus may be employed for example for the cooling of acids as described in Carter U. S. Patent No. 1,943,855 of January 16, 1934. In this case, one or both of the units of the apparatus of the invention may be used, and if one unit only is employed, it will be understood that a lower header similar to an upper header will be used instead of U-shaped bottom header 20 shown in the drawings.

The apparatus of the invention is also particularly adaptable for use in cooling of SO₂ burner gases in the manufacture of sulfuric acid. For example, the apparatus shown in Fig. 1 of the drawings may be employed in a wet purification system such as shown in Herreshoff U. S. Patent No. 940,595 of November 16, 1909, by placing the apparatus of the invention between the third cooling tower F² and the coke-box O of the Herreshoff patent. When so employed, the SO₂ burner gases are introduced into the upper header 13 through the open end 15 at temperatures of about 300° F. Water is fed into overflow boxes 44 on topsides of headers 13 and 23 so that the cooling water flows downwardly over the outer surfaces of the tubes in the form of continuous thin films. Flow of gas through the apparatus of Fig. 1 and rate of flow of cooling liquid over the outer surfaces of the tubes are controlled so that the gas leaving the rear end of header 23 is at temperatures of about 100° F. During passage of the SO₂ gases through the cooler moisture and sulfuric acid in the form of mist are condensed out, collect in the bottom of U-shaped header 20, and such condensate is withdrawn through outlet pipe 49. In this connection, it is noted that heat transfer is more efficient in the downflow unit 10 than in the upflow unit 11. In unit 10, the gas, vapors, and condensate formed are all flowing downwardly and downflow of the gas readily carries con-

densate along with the gas stream and formation of a liquid film on the inner tube walls is minimized. In unit 11, upflow of gas tends to impede the downflow of condensate with the result that the tendency toward film formation on the inner tube walls is increased with a corresponding decrease of heat transfer efficiency.

I claim:

1. Heat exchange apparatus comprising a plurality of tubes, each tube including a plurality of restricted throats and a plurality of chambers connected by a restricted elongated throat having an elongated cross-section the longest axis of which is disposed at an angle to the longitudinal axis of the tube, the axis of one throat being disposed at an angle to the axis of the next adjacent throat in said tube, adjacent tubes being arranged parallel and so that adjacent tube throat axes lying in the same plane are disposed at an angle to each other and at an angle to the plane of adjacent tubes, and means connecting adjacent tubes approximately at points where the ends of adjacent tube throat axes lying in the same plane most closely approach each other.

2. Heat exchange apparatus comprising a plurality of tubes, each tube including a plurality of restricted throats and a plurality of chambers connected by a restricted elongated throat having an elongated cross-section the longest axis of which is disposed at an angle to the longitudinal axis of the tube, the axis of one throat being disposed at an angle to the axis of the next adjacent throat in said tube, adjacent tubes being arranged parallel and so that adjacent tube throat axes lying in the same plane are disposed at an angle of about 90° to each other and at an angle of about 45° to the plane of adjacent tubes, and means connecting adjacent tubes approximately at points where the ends of adjacent tube throat axes lying in the same plane most closely approach each other.

3. Heat exchange apparatus comprising a plurality of tubes, each tube including a plurality of restricted throats and a plurality of chambers connected by a restricted elongated throat having an elongated cross-section the longest axis of which is disposed at a right angle to the longitudinal axis of the tube, the axis of one throat being disposed at a right angle to the axis of the next adjacent throat in said tube, adjacent tubes being arranged parallel and so that adjacent tube throat axes lying in the same plane are disposed at an angle of about 90° to each other and at an angle of about 45° to the plane of adjacent tubes, and means connecting adjacent tubes approximately at points where the ends of adjacent tube throat axes lying in the same plane most closely approach each other.

4. Heat exchange apparatus comprising headers and a plurality of tubes between said headers, each tube including a plurality of restricted throats and a plurality of chambers connected by a restricted elongated throat having an elongated cross-section the longest axis of which is disposed at an angle to the longitudinal axis of the tube, the axis of one throat being disposed at an angle to the axis of the next adjacent throat in the tube, adjacent tubes being arranged parallel and so that adjacent tube throat axes lying in the same plane are disposed at an angle to each other and at an angle to the plane of adjacent tubes, and means connecting adjacent tubes approximately at points where the ends of adjacent tube throat axes lying in the same plane most closely approach each other.

5. Heat exchange apparatus comprising upper and lower horizontal headers and a plurality of vertical tubes between said headers, each tube including a plurality of restricted throats and a plurality of chambers connected by a restricted elongated throat having an elongated cross-section the longest axis of which is disposed at a right angle to the vertical axis of the tube, the axis of one throat being disposed at a right angle 10 to the axis of the next adjacent throat in the tube, adjacent tubes being arranged vertically and so that adjacent tube throat axes lying in the same horizontal plane are disposed at an angle of about 90° to each other and at an angle 15 of about 45° to the plane of adjacent tubes, spot welds connecting adjacent tubes approximately at points where the ends of adjacent tube throat axes lying in the same plane most closely approach each other, and means for flowing fluid 20 heat transfer medium in the form of relatively thin films over the surface of said tubes.

6. Heat exchange apparatus comprising a plurality of tubes, each tube including a plurality of chambers connected by a restricted elongated throat having an elongated cross-section the longest axis of which is disposed at an angle to the longitudinal axis of the tube, adjacent tubes being arranged parallel and so that adjacent tube throat axes lying in the same plane are disposed 25 at an angle to each other and at an angle to the plane of adjacent tubes, and means connecting adjacent tubes approximately at points where the ends of adjacent tube throat axes lying in the same plane most closely approach 30 each other.

7. Heat exchange apparatus comprising a plurality of tubes, each tube including a plurality of chambers connected by a restricted elongated throat having an elongated cross-section the longest axis of which is disposed at an angle to the longitudinal axis of the tube, adjacent tubes being arranged parallel and so that adjacent tube throat axes lying in the same plane are disposed 40 at an angle of about 90° to each other and at an angle of about 45° to the plane of adjacent tubes, spot welds connecting adjacent tubes of a unit approximately at points where the ends of adjacent tube throat axes lying in the same horizontal plane are disposed 45 at an angle of about 90° to each other, and means connecting adjacent tubes approximately at points where the ends of adjacent tube throat axes lying in the same plane most closely approach each other.

- 50 8. Heat exchange apparatus comprising a plu-

rality of units each including headers and a plurality of tubes between said headers, each tube including a plurality of restricted throats and a plurality of chambers connected by a restricted elongated throat having an elongated cross-section the longest axis of which is disposed at an angle to the longitudinal axis of the tube, the axis of one throat being disposed at an angle to the axis of the next adjacent throat in the tube, adjacent tubes in a unit being arranged parallel 10 and so that adjacent tube throat axes lying in the same plane are disposed at an angle to each other and at an angle to the plane of adjacent tubes, means connecting adjacent tubes of a unit approximately at points where the ends of adjacent tube throat axes lying in the same plane most closely approach each other, and means for flowing fluid medium first through the tubes of one unit and then through the tubes of a succeeding unit. 15

9. Heat exchange apparatus comprising a plurality of vertically disposed units each including horizontally disposed upper headers, a common lower header and a plurality of vertical tubes between said upper and lower headers, each tube including a plurality of restricted throats and a plurality of chambers connected by a restricted elongated throat having an elongated cross-section the longest axis of which is disposed at a right angle to the vertical axis of the tube, the axis of one throat being disposed at a right angle to the axis of the next adjacent throat in the tube, adjacent tubes in a unit being arranged vertically and so that adjacent tube throat axes lying in the same horizontal plane are disposed 20 at an angle of about 90° to each other and at an angle of about 45° to the plane of adjacent tubes, spot welds connecting adjacent tubes of a unit approximately at points where the ends of adjacent tube throat axes lying in the same horizontal plane are disposed 25 at an angle of about 90° to each other, and means connecting adjacent tubes approximately at points where the ends of adjacent tube throat axes lying in the same horizontal plane most closely approach each other, an overflow trough associated with each upper header and arranged to flow liquid in thin films 30 downwardly over the surface of tubes of each unit, and means for flowing fluid medium first 35 downwardly through the tubes of one unit, through the common lower header and then upwardly through the tubes of a succeeding unit. 40
